UNITED STATES PATENT OFFICE.

JEROME S. MUNGER, OF EDENBURG, (KNOX P. O.,) PENNSYLVANIA, ASSIGNOR OF ONE-HALF OF HIS RIGHT TO WILLIAM M. KIRKPATRICK AND ONE-FOURTH TO EUGENE J. LITTLE, OF SAME PLACE.

CUTTER FOR REMOVING WELL-CASINGS.

SPECIFICATION forming part of Letters Patent No. 224,465, dated February 10, 1880.

Application filed June 14, 1879.

To all whom it may concern:

Be it known that I, JEROME S. MUNGER, of Edensburg, (Knox P. O.,) in the county of Clarion and State of Pennsylvania, have invented a new and valuable Improvement in Cutters for Removing Well-Casings; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a sectional elevation of my cutter. Fig. 2 is a detail view thereof. Fig. 3 is a cross-section, and Fig. 4 is a bottom view of the same.

This invention has relation to improvements in cutters for removing well tubes or casing by producing a cut or slot in each side of the tube or casing; and it consists of a cylinder or tube armed with rotary cutters hung upon axes secured in movable blocks in the cylinder, with their opposite ends acted on by a conical plunger which is subjected to the jarring action of a tubular hammer or driver, substantially as hereinafter more fully set forth.

In the accompanying drawings, A refers to a cylinder or tube with its lower end plugged up, as at a', and provided therewith a number of radial springs, a a, whose free ends are designed to press or bear against the inside of the well-casing. By this arrangement it will be noticed that as the free ends of the springs spring past the joint of each section of the casing, or from the casing to the wall of the well, which will be attended with more or less sound or concussion, the completion of the cutting of each length or section of the well-casing will be thus indicated, as will be also the passing of the cylinder, with its cutters, from the casing to the walls of the well when the springs have reached the lower end of the casing. The upper end of this cylinder is provided with an inner screw-thread, to permit the attachment thereto of suitable means for

imparting a vertically-vibrating motion to the cylinder in the casing necessary to cause its cutters to cut or slot the casing.

B B are the cutters, which consist of rotary knife-edged disks arranged, two in number, on each side of the cylinder A, and are hung in movable blocks C C upon axes b b secured in the latter, which blocks are disposed in lateral openings c c in the cylinder, communicating with the vertical passage thereof, which receives the tapering or conical plunger D. The plunger D wedges itself in between the inner or concaved opposite ends of the blocks C C, carrying the cutters B. The action of the plunger D on the blocks as it is forced downwardly by the hammer or driver is to effect the lateral movement of said block with its cutters and cause the latter to cut a piece out of each side, and in the direction of the length of the well-casing, by which the casing may be collapsed and removed by suitable means. Simultaneously with this movement the cutters also partake of the vertical movement of the cylinder A, to cause them to effect both a vertical and lateral cut in the casing. The plunger D is provided at d with an annular head or enlargement upward, from which point it is provided with a guide-rod, e, having a head, e'.

E is the hammer or driver, tubular in form, and fitting upon the guide-rod e of the plunger D, with its lower end provided with an inwardly-projecting annular flange, f, to prevent its detachment from the plunger, the said flange intercepting the head e' on the guide-rod e of the plunger when the hammer has been lifted. The upper end of the hammer or driver E is adapted (by having preferably a hole through it) to permit the attachment thereto of a rope or cord for lifting and letting it fall on the plunger, its lower end striking the head or enlargement d of the plunger. This action of the hammer or driver drives the conical or tapering plunger D in between the cutter-carrying blocks, and, as above intimated, causes the cutters to sever the casing.

The cutter-carrying cylinder A has attached

to it in any suitable manner a rope, cord, or chain, by which it may be withdrawn when desired.

What I claim as new and desire to secure by Letters Patent, is—

1. In combination with the cylinder A, carrying the cutters B, the conical plunger D and its hammer E, the whole arranged to operate as shown and described.

2. In combination with the plunger D, provided with the flange d, adapted to rest upon a shoulder in the cylinder A, hammer E, fitting over the headed stem e, and confined

thereon by a flange, f, substantially as specified.

3. In a well-casing cutter, the cylinder A, provided at its lower end with the radial springs a a, substantially as and for the purpose specified.

In testimony that I claim the above I have hereunto subscribed my name in the presence of two witnesses.

JEROME S. MUNGER.
